UNITED STATES PATENT OFFICE.

EDMUND WANDNER, OF CHICAGO, ILLINOIS.

X-RAY TUBE.

1,359,300.

Specification of Letters Patent. Patented Nov. 16, 1920.

Application filed July 21, 1919. Serial No. 312,194.

To all whom it may concern:

Be it known that I, EDMUND WANDNER, a citizen of the United States, residing at Chicago, in the county of Cook and State of Illinois, have invented certain new and useful Improvements in X-Ray Tubes; and I do declare the following to be a full, clear, and exact description of the invention, such as will enable others skilled in the art to 10 which it appertains to make and use the same.

This invention relates to X-ray tubes, and it relates more specifically to an improved heating unit and associated regulator.

15 One object of this invention is to provide an improved X-ray device including a manually controlled regulator by means of which a very steady or uniform vacuum can be maintained in the X-ray tube, and by 20 means of which the vacuum can be lowered so as to prevent the tube from being punctured, and from being distorted to such extent as to destroy or impair the focus of the tube.

25 Another object is to provide an improved device of this character which affords the operator an easy and direct control of the current and also provides a fine range whereby he can obtain a steady vacuum in 30 the tube.

Another object is to provide for effectually regulating the electric current strength and thereby generating a greater or less quantity of metallic gases within the tube, 35 according to varying circumstances.

Another object is to efficiently heat the vacuum tube, by the employment of a low tension current such as derived from an ordinary electric lamp socket.

40 Another object is to provide for regulating the vacuum, without disconnecting the current, by simply varying the current.

Another object is to provide a device of this character which is extremely durable 45 and thoroughly practical.

Other objects and advantages may become apparent to persons who read the following details of description in connection with the accompanying drawings, in which:

50 Figure 1 is a side elevation of my improved vacuum tube in connection with the lead for connecting it to an external source or current of electricity.

Fig. 2 is an enlarged detail view, partly 55 in longitudinal section.

Fig. 3 is a perspective view of the heating coil and its adjuncts.

Referring to these drawings in detail, in which similar reference characters correspond with similar parts throughout the several views, the vacuum tube comprises a transparent bulb 5 having diametrically opposite extensions 6 and 7 which contain the usual anode 8 and cathode 9, respectively, and the vacuum tube also comprises a hollow extension 10 which is formed integrally with the bulb 5 and with a tubular element 11 such as illustrated in detail in Fig. 2. The parts 5, 6, 7, 10 and 11 are preferably formed integrally of glass, and are, therefore, both transparent and insulating.

Referring now particularly to Fig. 2, it will be seen that a screw-plug 12, adapted to fit an ordinary electric lamp socket, receives the outer end of the tubular element 11 75 where it merges with the outer end of the extension 10; and this plug 12 is also adapted to fit a regulator or rheostat-socket such as illustrated at 13 in Fig. 1, this socket being provided with a regulating handle 14 80 whereby the resistance and current strength may be regulated in the well known manner.

A conducting wire is connected with the hollow elements 10, 11 and 12 in the following manner: A wire of relatively high resistance has its major portion coiled about the inner end of the tubular element 11 as indicated at 15, a sheet of mica 16 being preferably disposed between the tubular element 11 and the coil 15. The ends of this wire connect with terminal wires 17 and 18 at points indicated at 19, and an intermediate portion of this high resistance wire extends through an aperture 20, thence toward the inner end of the tubular element and out through a notch 21 formed in the inner end of the said tubular element. This tubular element 11 is formed with a partition 22 at its middle portion, so that air or gas can 95 pass therethrough, and at the opposite side of this partition from the aperture 20, the tube is provided with two apertures 23 through which the terminals 17 and 18 extend from the exterior, at 19, to the interior 100 at 23, and these terminals connect respectively to the metallic shell of the screw-plug 12 and to the usual contact element 24, as indicated in Fig. 2.

It is understood, of course, that the inner 110

end portions of the terminals 17 and 18 completely fill and seal the apertures 23. Although I have found it convenient to connect the high-resistance or heating wire to the terminals 17 and 18 as indicated in Fig. 2, it is not beyond the scope of this invention to dispense with the joints 19 and extend the high-resistance wire into the screw-plug 12 in lieu of the terminals 17 and 18.

10 Referring now to Fig. 3, it will be seen that the high-resistance wire 15, after passing outward through the notch 21, is interlocked with the lower or inner turn of the coil as indicated at 25, and although this 15 short-circuits the lower turn to a certain extent, it is advantageous in that it secures the coil in a definite and fixed relation to the tubular element 11. It is to be understood, of course, that any appropriate number of 20 turns may be employed in the heating coil, and that the turns of the coil may be insulated from one another in any appropriate way.

Referring again to Fig. 1, it will be seen 25 that the lower or inner end of the heating unit, shown in Fig. 2, terminates approximately at the central portion of the bulb 5, that is, approximately at the path of current between the anode and cathode 8 and 9, and 30 therefore, this metallic resistance coil not only generates heat within the bulb 5, so as to regulate the vacuum, but it also generates the metallic gas which constitutes the conducting medium between the anode and 35 cathode. Moreover, it will be seen that the regulator 13 is directly connected to the heating unit, and is located in the most convenient position for easy and effective control by the operator.

40 Although I have shown the element 16 disposed in contact with the tubular element 11, it is within the scope of this invention to dispose a metallic sheet or tubular element between the mica 16 and the adjacent 45 part of the tubular element 11 so that the heating of such metallic element by the coil 15 would increase the generation of metallic gas, and this increase of the metallic gas can be predetermined by the thickness of the 50 sheet of metal within the coil 15.

Although I have described this embodiment of my invention very specifically, it is to be understood that my invention is not limited to these exact details of construction 55 and arrangement of parts, but I am entitled to make changes within the scope of the inventive idea disclosed in the foregoing description and following claims.

What I claim as my invention is:

60 1. In an X-ray device, the combination of an anode, a cathode, a transparent bulb provided with tubular extensions through which said anode and cathode coöperate, a combined heater and regulator comprising a tubular element extending into said bulb at a

point spaced from said tubular extensions, a manually controllable current-regulating means on the outer end of said tubular element, terminal wires electrically connected to said current regulating means and extending thence toward the opposite end of the tubular element, and a heating coil around the said opposite end of said tubular element and being electrically connected to said terminals.

70 2. In an X-ray tube, the combination of an anode and a cathode, and an electric heating unit spaced from said anode and cathode and extending from the exterior of the tube to its interior and having its outer end terminating in an ordinary screw plug to fit in and electrically connect with a lamp socket, the inner end of the heating unit terminating adjacent to the center of the space between the anode and cathode.

75 3. In an X-ray tube, the combination of an anode, a cathode, a transparent bulb provided with tubular extensions through which the anode and cathode coöperate, a tubular element formed integrally with and extending from the exterior approximately to the center of the interior of the bulb, this tubular element being spaced from said tubular extensions, a heating and gas generating coil of wire encircling the inner end of said tubular element and supported by the latter, and conducting terminals extending through the outer part of said tubular element and electrically connectible with a 80 source of electric current.

85 4. In an X-ray tube, the combination of an anode, a cathode, a transparent bulb provided with tubular extensions through which the anode and cathode coöperate, a tubular element extending from the exterior to the 90 interior of the bulb and being internally sealed to maintain the vacuum in the bulb, this tubular element being spaced from said tubular extensions and having its inner end approximately at the center of said bulb, a 95 heating and gas generating coil around and supported by the inner end portion of said tubular element, conducting terminals extending from the exterior to the interior of the tube and connecting with said coil, and a hollow electric connector fitted on the 100 outer end of said tubular element and having said terminals electrically connected thereto in insulated relation to one another and thereby adapted to be electrically connected to a corresponding connector of an 105 external source of electricity.

110 5. In an X-ray tube comprising a transparent bulb, a tubular insulating element extending from the exterior to the interior 115 of the bulb and having an air-sealing partition in its intermediate part and an aperture between the partition and the inner end of the tubular element, said inner end having a notch therein, a pair of terminal 120

wires extending from the exterior to the interior of said tubular element at points outwardly beyond the partition and thence extending outward through said tubular element so that their outer ends may be connected with external electric conductors, and a heating wire having its ends connected respectively to the inner ends of said terminal wires, the major part of said heating wire 10 being coiled about the portion of the tubular member inward of its partition, a minor part of the heating wire extending into the tubular element through said aperture and thence inward through said tube to and 15 through said notch.

6. The combination of a tubular element having a partition intermediate of its ends

and having apertures therein at one side of the partition and an aperture at the opposite side of the partition and a notch in the 20 end at the said opposite side, and conducting wire comprising a coil around said tubular element and a portion extending through said notch and through the interior and the last said aperture of said tubular element, 25 said wire also comprising terminals which extend through the first said apertures and thence through the interior of said tubular element toward the end opposite the end containing said notch.

In testimony whereof I have hereunto set my hand.

EDMUND WANDNER.
